BY
George C. Heinrich
ATTORNEY

UNITED STATES PATENT OFFICE.

BRONISLAW KACZMARSKI, OF DETROIT, MICHIGAN.

BEET TOPPER.

Application filed January 12, 1923. Serial No. 612,221.

To all whom it may concern:

Be it known that I, BRONISLAW KACZMARSKI, a citizen of Poland, residing at Detroit, county of Wayne, and State of Michigan, have invented certain new and useful 5 Improvements in Beet Toppers, of which the following is a specification.

This invention relates to improvements in agricultural machines, particularly in beet 10 toppers, and it is the principal object of my invention to provide a plurality of reciprocating knives or cutters which will serve to sever the top of a plurality of beets simultaneously.

Another object of the invention is the 15 provision of a machine of this character provided with means for guiding the beets under the knives.

A further object of the invention is the 20 provision of a beet topper and provided with means whereby the tops will be carried out to one side.

A still further object of the invention is the 25 provision of means for removing the topped beets to a collector or washing means.

With these and other ends in view my 30 invention consists in the improved construction, arrangement and combination of parts more fully to be described hereinafter and then particularly pointed out in the claim.

In the accompanying drawing, forming 35 a material part of this invention.

Figure 1 is a side elevation of a beet topper 40 constructed according to my invention.

Figure 2 is a top plan view of the same.

Figure 3 is a side elevation, partly in section on line 3—3 of Figure 4.

Figure 4 is a front elevation of the 45 machine.

Figure 5 is a section on line 5—5 of Figure 1.

Figure 6 is a detail view showing one of the conveyors in top plan view, and

Figure 7 is a side elevation thereof.

The machine comprises a frame or bed 50 on which is supported by a plurality of uprights 11, a table 12 carrying intermediate its ends a frame comprising pairwise arranged vertical end posts 13, the upper ends of which are connected by horizontal beams 14, while pairwise arranged horizontal upper beams 15 and lower beams 16 connect the pairs of end posts 13. A crank

shaft 17 is journaled with its ends in beams 55 14 and projects beyond the same.

To the crank arms 18 and 19 of shaft 17, the upper ends of links 20 and 21 are secured, to the lower ends of which are pivotally attached the frame bars 22 and 23 for 60 the exchangeable knife blades or cutters 24 and 25.

The outer end of shaft 17 carries a pulley 26, over which a belt 27 is guided, which is also guided over a pulley 28 on a shaft 29 journaled in the machine frame and carrying at its other end beyond the frame a sprocket wheel 30 and a drive pulley 31, adapted to be rotated by means of a belt or other suitable device from a motor or the belt pulley of a locomobile etc. A chain 32 is guided over sprocket wheel 30 and a sprocket wheel 33 on a shaft 34 journaled transversely in the machine frame, and shaft 34 carries on the opposite side of the machine frame a sprocket wheel 35, over which a chain 36 is guided, which is also guided over a sprocket wheel 37 on a shaft 38 journaled in the frame at one end, and in a vertical bar 39 within the frame at its opposite end. 70

Shaft 38 carries at its outer end beyond bar 39 a bevel gear 40 in mesh with a larger bevel gear 41 at the end of a shaft 42 journaled in the machine frame and extending beyond the front wall of the same where it carries a pulley 43, over which a belt 44 is guided, which is also guided over a pulley 45 on a shaft 46 journaled in two of the front posts of the frame designated 47 and 48 in the drawing. At its opposite end the shaft 46 carries a sprocket wheel 49, over which a chain 50 is guided, which is also guided over a lower sprocket wheel 51 on shaft 52 journaled in the frame between posts 47 and 48, and which carries at its opposite end a pulley 53, over which a belt 54 is guided, which is also guided over a pulley 55 on a transversal shaft 56 of an auxiliary conveyer 57 in a frame composed of side bars 58 and 59. 80

The conveyer 57 carries partitions 60, and brackets 61 and 62 are attached to one of the ends of bars 58 and 59 to allow an attachment of the auxiliary conveyer 57 to links 63 and 64, as best shown in Figure 4. 90

A small roller 65 is journaled between bars 58 and 59 for guiding the conveyer 57. 100

Conveyer belts 66 and 67 are guided over sprocket wheels 68 on shaft 69 journaled in the rear part of table 12, and over shaft 34 and are provided with transverse partitions 70.

Posts 71 are vertically erected on the rear of the machine frame and their upper ends are connected by a cross beam 72, in which the ends of strong leaf springs 73 and 74 (Figure 2) are secured, which press with their outer free ends formed into leaves upon the beets transported by conveyers 66 and 67.

A conveyer belt 75 is transversely guided 15 through the machine under the knives or cutters at one end over shaft 42, and at its opposite end over a shaft 76, while another conveyer belt 77 is guided in the front part of the machine over shaft 46 and a roller 20 78 journaled in the frame.

The machine operates as follows:

The beets are placed upon the conveyers 66 and 67 which will guide the beets under the springs 73 and 74 when the machine is 25 started by rotating pulley 31 on shaft 29 from a suitable motor.

Shaft 29 carries on the opposite side of the machine a pulley 28, over which belt 27 is guided, which is also guided over pulley 30 26 on crank shaft 17, so that during the rotation of the shaft 17 the knives will execute a vertical reciprocating motion.

The rotation of shaft 29 will be communicated by means of pulley 28 and chain 32 35 to sprocket wheel 33 on shaft 34, over which the conveyers 66 and 67 are guided.

The beets 79 will be guided by conveyers 66 and 67 under the pressure of springs 73 and 74 under the knives 23 and 24 to be 40 topped in an obvious manner.

Shaft 34 carries at its opposite end the pulley 35, which is connected by means of belt 36 to pulley 37 on shaft 38. Shaft 38 carries bevel gear 40 which is in mesh with 45 bevel gear 41 on shaft 42, which will be rotated and over which conveyer 75 is guided, which is also guided over roller 76. This conveyer 75 is directly beneath the knives and the conveyers 66 and 67 so that the 50 cut off tops of the beets will fall between

conveyers 66 and 67 upon conveyer 75 and will be carried towards the side of the machine.

The topped beets will be carried along on conveyers 66 and 67 until they are 55 dropped upon conveyer 77 which is running over shaft 78 by the rotation of shaft 42 and the intermediary of pulley 43, belt 44 and pulley 45 on shaft 46.

Shaft 46 in turn communicates its rotation by means of pulley 49 and belt 50 to pulley 51 on shaft 52 which carries pulley 53 over which a belt 54 is guided, which is also guided over the pulley 55 of auxiliary conveyer 57 so that the topped beets 60 are delivered by this conveyer to a collecting vessel, car or washer.

It will easily be seen that my invention may be varied in many ways without departing from the principles which are the 70 basis of the same.

What I claim as new and desire to secure by Letters Patent is:

In a beet topper, a crank shaft, a pair of vertically reciprocating knives secured to 75 said shaft to operate upon the rotation of said shaft, a pair of spaced conveyer belts guided longitudinally through the topper adapted to receive the beets to be topped, the inner edges of said belts directly under 80 and parallel to the cutting edges of said knives, a transversal conveyer belt directly under said knives for discharging the cut off tops, a transversal conveyer belt in front of the ends of said pair of conveyer belts, 85 links attached to the frame of the topper, an auxiliary conveyer adapted to be attached to said links to form a continuation of said last named transversal belt for discharging the topped beets, means for simultaneously operating said knives and conveyers to perform their respective functions, and a pair of strong leaf springs adapted to press the beets against said pair of conveyer belts to allow an operation of the 90 knives for removing their tops.

In testimony whereof I have affixed my signature.

BRONISLAW KACZMARSKI.
